UNITED STATES PATENT OFFICE.

JACKSON L. KAIL, OF CHICAGO, ILLINOIS.

DOOR-HANGER.

1,033,177.

Specification of Letters Patent. Patented July 23, 1912.

Application filed October 21, 1911. Serial No. 655,841.

To all whom it may concern:

Be it known that I, JACKSON L. KAIL, a citizen of the United States, residing at Chicago, in the county of Cook and State 5 of Illinois, have invented new and useful Improvements in Door-Hangers, of which the following is a specification.

This invention relates to door hangers and has for its main object to provide a simple 10 door hanger of improved, novel construction, arranged to slidably support elevator doors, gates or other doors, upon a suitable track.

Another object is to provide improved 15 means in a door hanger, whereby a limited amount of vertical adjustment may be given the hanger frame to properly position the lower edge of the door with respect to the grooved sill in which said lower edge 20 travels.

Other objects and advantages will appear in the course of this specification, and with all of said objects and advantages in view, this invention consists in the several novel 25 features of construction, arrangement and combinations of parts hereinafter set forth and particularly defined in the claims.

The invention is clearly illustrated in the drawing furnished herewith, in which:

30 Figure 1 is a face view of a fragment of an elevator door and supporting track showing a pair of my improved door hangers used in connection therewith; Fig. 2 is a detail face view, looking at the opposite 35 side of the hanger and door; Fig. 3 is a detail vertical section taken on the line 3—3 of Figs. 1 and 2; Fig. 4 is a plan, with certain portions broken out to illustrate parts that would otherwise be hidden from view 40 and Fig. 5 is a face of one of the arms of the roller carrying member that forms part of the hanger frame.

Referring to said drawing, A, represents 45 a track supported by a member B, of the inclosure, in the usual manner, said track being here shown in the form of a bar α , having a longitudinally extending groove in its upper side, in which run the rollers of the hanger. An angle iron α^1 projects up 50 from the side of the bar α , and has a horizontal flange α^2 , overhanging the rollers of the hanger. A fragment of a door is seen at C; it is carried by the hangers D, which are secured to the top of the door and slid- 55 ably connect the door with the track.

My improved hanger is best seen in the

enlarged views, and in the preferred embodiment of the invention comprises a pair of rollers 10, journaled on a roller carrying member 11, mounted on a bracket 12, which 60 is riveted or otherwise secured to the upper edge of the door C. Said roller carrying member 11, is shown as forked upon its ends to receive the rollers 10, and I have illustrated anti-friction bearings between said 65 rollers and the pins 13, upon which they are journaled. Said anti-friction bearings are here shown as comprising a plurality of small rollers 13^a, arranged within the hub of each roller and surrounding a sleeve 13^b, 70 that extends between the two fork members of the roller carrying member. The pin 13, extends through said fork members and sleeve, and is in the form of a rivet, the ends of which are upset on the outer face of 75 said fork member.

The roller carrying member is shown as fulcrumed upon the bracket 12, in a horizontal line, whereby said member may be capable of oscillation upon said bracket; 80 this construction provides means whereby the rollers 10, may follow any slight irregularities in the tread of the track, without any appreciable jar or shock to the door. The means here shown for affording such 85 pivotal connection, comprises a screw 14, and a washer 15, the screw extending through said washer and being threaded in the roller carrying member, midway between the journals of the rollers 10. The 90 washer 15, is preferably countersunk in the bracket 12, and has a reduced neck 16, that turns in a hole 17, formed in the bracket 12, and said reduced neck is made a trifle thicker than the body of the bracket at the 95 point where said neck passes through the same, thus allowing little play between said bracket and the adjacent faces of the roller carrying member 11, and washer 15. This construction permits the roller carrying 100 member 11, to oscillate freely upon its fulcrum without any danger of unscrewing the screw 14.

The roller carrying member 11, is shown as comprising two arms 18, 18, that are arranged to be secured together in various angular positions with respect to each other, to afford the vertical adjustment for the hanger. As here shown, each arm 18, has a jaw 19, surrounding the screw 14, and preferably formed with radial serrations or teeth 20, upon one face, the teeth of one jaw being

arranged to co-act with the teeth of the other jaw to prevent angular movement of one arm with respect to the other when said jaws are held together. In the form shown 5 in the drawings, the same screw 14, which secures the roller carrying member 11, to the washer 15, in their pivotal connection with the bracket, acts to secure together the two arms 18, to provide a rigid roller supporting member, capable of vertical oscillation up the bracket.

To reduce the noise usually attendant in door hangers, I provide peripheral grooves 15 in the rollers 10, in which grooves are seated tires 21, made of suitable material such as rubber, babbitt, leather or the like. Said tires, in running over the metal track, reduce the noise to a minimum.

In hanging a door provided with my improved hangers, if it is found that the door is hung too low, so that its lower edge strikes the sill, or if the door is too high and out of sliding engagement with the sill, the door may be raised or lowered with respect to 25 the track, by simply unscrewing the screw 14, raising or lowering the door to the proper position, and then screwing up the screw 14, to clamp the jaws together. In Fig. 2 I have shown (in dotted lines) the 30 door lowered considerably from a position that it occupies when the two arms of the roller carrying member are in alinement with each other. Thus when the door is lowered or raised, the two arms 18, assume 35 positions that are angularly disposed with each other, thus raising or lowering the pivot point of the roller carrying member, but in no wise affecting the perfect operation of the hangers.

40 I realize that various alterations and modifications of this device are possible, without departing from the spirit of my invention, and I do not therefore desire to limit myself to the exact form of construction shown and described.

I claim as new and desire to secure by Letters Patent:

1. A door hanger comprising a bracket arranged to be secured to a door, a two 50 armed roller-carrying member mounted on said bracket, the two arms of said roller carrying members overlapping one another and being rigidly clamped together, but having a limited amount of angular adjustment with respect to each other in a vertical 55 plane, and a pair of rollers adapted to run upon a suitable track, one journaled on each arm of said roller-carrying member.

2. A door hanger, comprising a bracket

adapted to be secured to a door, an oscillatory 60 two armed roller-carrying member fulcrumed on said bracket on a common pivot, the two arms of said bracket being rigidly secured together, but capable of relative angular adjustment, and a pair of rollers 65 adapted to run upon a suitable track, one roller being journaled on each arm of said roller-carrying member, near its outer end.

3. A door hanger comprising a bracket 70 adapted to be secured to a door, a two armed roller carrying member mounted on said bracket, two arms of said roller-carrying member having co-acting jaws arranged to be clamped together with the arms adjusted to any of a number of angularly disposed 75 positions with respect to each other, clamping means therefor and a pair of rollers adapted to run upon a suitable track and journaled on said arms.

4. A door hanger, comprising a bracket 80 adapted to be secured to a door, a two armed roller-carrying member, each arm being formed with a toothed jaw, the one jaw engaging the other jaw, a screw extending through said bracket and arms, said screw 85 being arranged to secure said arms together in any of several angular positions with respect to each other, and to pivotally secure said roller-carrying member to the bracket, and rollers one journaled at each end of said 90 roller-carrying member.

5. A door hanger, comprising a bracket 95 adapted to be secured to a door, a two armed roller-carrying member secured to said bracket, each arm of said roller carrying member having a toothed segmental jaw, the one engaging the other, said jaws being clamped together to form a rigid member, and rollers one journaled at the end of each arm.

6. In a door hanger, the combination with a bracket formed with a bearing aperture therein, a washer having a neck journaled in said bearing aperture, a roller-carrying member comprising two angularly adjustable arms having co-acting jaws, a screw extending through said washer and jaws and acting to clamp together said jaws and washer, and rollers one journaled at each end of said roller-carrying member.

In witness whereof, I have hereunto signed my name at Chicago, Cook county, Illinois, this 19th day of October 1911.

JACKSON L. KAIL.
